ERNEST J. SHAFFER, OF TULSA, OKLAHOMA

SLIP SOCKET

Application filed November 29, 1920. Serial No. 426,974.

This invention relates to slip sockets that are used for recovering broken or disconnected sucker rods from oil wells and the like.

The primary object of my invention, is to provide a self-contained slip socket that will run freely in well tubing of a given diameter and catch any and all breaks that are possible of occurring in standard sucker rods designed to operate in said tubing, avoiding the necessity of employing different sockets for grasping, respectively, the rods and their boxes or couplings (the part to be caught depending upon the location of the break in the rod); and eliminating the need of interchangeable slips for grasping rods of different diameters and couplings of various sizes.

More specific objects of the present invention are the provision of a tool of the aforementioned character incorporating slips that will adapt themselves readily to rods of different diameters as well as to couplings of different sizes and in all instances will operate with a high degree of efficiency; the provision of slips that will adjust themselves easily and quickly to the nature of the break; that will operate the minimum friction in the barrel; and the provision of means for positively maintaining the slips in operative relation to each other at all times and for preventing the accidental dislodgment of a slip from the barrel.

The foregoing objects, and others which will become apparent as this description proceeds, are attained in the slip socket illustrated in the drawings accompanying and forming a part hereof and wherein Fig. 1 is a central longitudinal section through a slip socket constructed in accordance with my invention; Fig. 2 is a section on the line 2-2 of Fig. 1; Fig. 3 is a fragmentary perspective view of the set of slips; Fig. 4 is a diagram showing the manner in which I cut the slips from a blank of circular cross section; Fig. 5 is a bottom end elevation of the slip socket, disclosing the effect of so cutting the slips; and Figs. 6, 7 and 8 show the socket executing various catches in well tubing.

The socket is composed of a barrel 1, a cap 2 that is screwed into the upper end of the

barrel, a set of slips 3 that occupy the lower portion of the barrel, and a spring 4 interposed between the cap and slips and which tends to depress the latter. This combination, in itself, is old and I make no claim to it except as it is affected by the improvements, residing principally in the barrel and slips, which my invention imports into it and whereon the attainment of the objects above enumerated are dependent.

The barrel 1, which is preferably formed of seamless steel tubing of high tensile strength, is shown as cylindrical on its exterior from end to end. The bottom of the barrel is chamfered upwardly and inwardly to provide an inclined guide wall 5 that surrounds what may be termed the mouth of the socket. For convenience of description, the barrel may be divided into zones *a*, *b*, *c*, and *d*. Throughout zone *a* the interior of the barrel is threaded for the attachment of cap 2 and the wall is made sufficiently thick to afford a substantial screw connection. Throughout the length of zone *b*, except where it joins the threads of zone *a*, the barrel is reamed out to provide the greatest possible internal diameter while preserving the requisite strength of wall. Immediately below zone *a*, the inner wall diverges to provide a tapered shoulder *a'*. Zone *c* represents a rather abrupt inward taper of the wall, which breaks over a shoulder 6 into a long and gradual taper that extends to the mouth of the barrel or socket, or, in other words, throughout the length of zone *d*. This portion I shall refer to as the "choke" of barrel.

Here it may be explained that the barrel is of substantially the maximum diameter that will operate practically within tubing of a size wherein the socket is designed to work; and that the mouth of the barrel is of a diameter approximately five sixths of the external diameter of the barrel. It is through these proportions that the socket is capable of admitting couplings of standard size sucker rods constructed to operate in said tubing.

The design of the slips may be best described by explaining briefly how the slips are at present made. A blank 20^a of circular cross-section (shown in end elevation in Fig.

4) is formed from a suitable piece of stock to a shape approximately the same as that of the choke of the barrel but of somewhat greater diameter, and it is provided with a central through opening that decreases in diameter from the lower to the upper end of the blank (considering its ultimate position in an upright barrel). The opening, in fact, is divided into two compartments, one of a diameter to receive boxes or couplings, and the other of a size to receive rods. The blank is then cut into three segments, as indicated by the dotted lines of Fig. 4, the material between the two lines representing the breadth of each cut being thus removed. Therefore, when the segments are brought together and inserted fully into the choke of the barrel, as shown in Fig. 1, the arcs of the segments or slips are somewhat eccentric with respect to the bore of the barrel. This reduces the frictional contact between the slips and barrel and allows the slips to slide more readily than if they bore throughout their entire surfaces upon the barrel. It will be seen presently, however, when the operation of the socket is described, that as the slips recede within the choke they expand to the original diameter of the blank 20^a and assume a concentric relationship within the barrel. Adjacent their edges, the slips are dressed off so as to prevent the edges from cutting into the barrel.

Returning now to the opening of the slips, the box or coupling receiving compartment 35 is designated 3^a and the rod receiving compartment, 3^b. Both are provided with upwardly directed teeth, and they are separated by a bulged guide wall 3^c. The walls of compartment 3^a converge slightly from their lower ends where the normal diameter of the compartment is substantially equal to or slightly less than that of the mouth of the barrel, upwardly to about the vertical center of the compartment and are shown as parallel thereabove; while the walls of compartment 3^b converge slightly from their lower to their upper ends where the normal diameter of the compartment is less than one third the external diameter of the barrel. The slips, considered collectively, are reduced in diameter at their upper ends to provide a depressed seat 10 for spring 4; and immediately below the plane of the seat, each slip is provided on one side with a recess 11, for the reception of a lug 12 that projects from the near side of the adjacent slip. It is the interengagement of these lugs and recesses that maintains the slips in operative relation to each other and prevents the accidental dislodgment of the individual slips from the barrel.

The cap 2 is provided with the usual pin 15 for attaching the socket to a line or sucker rods or the like by means of which the socket is lowered into and withdrawn from the well

during the "fishing" operation. It will be noted from an inspection of Figs. 6 to 8 that there is little clearance between the socket and the well tubing A, wherefore it is advantageous to provide cap 2 with a port 16 for the free passage of air and liquid as the socket is lowered into the well.

In Fig. 6 the socket is shown as catching a sucker rod B that has broken at a point intermediate its couplings. In executing such a catch, the socket is lowered until it engages the end of the rod, and, if the rod is at one side of the tubing, the guide wall 5 will direct it into the mouth of the socket. Likewise the rod will be centralized within the slips by following the wall of compartment 3^a and the guide wall 3^c until it enters the rod receiving compartment 3^b. As the rod B finds its diameter within the compartment 3^b it will practically arrest the downward movement of the slips. The barrel, however, will continue to descend against the action of spring 4 so that the slips are withdrawn somewhat from the choke of the barrel and allowed to expand to admit the rod further into compartment 3^b; the slips in the meanwhile rocking over the shoulder 6 of the barrel to bring the walls of the compartment 3^b more into parallelism so that a bite of greater length may be had on the rod and the tenacity of the catch thus enhanced. When a hold is thus effected, the socket is elevated, and with it the entire string of sucker rods to which the socket has automatically attached itself. It is obvious that as the weight of the rods is imposed upon the slips it will cause them to wedge themselves into the choke of the barrel which further increases the firmness of the hold.

The catch illustrated in Fig. 7 is one imposed upon a box or coupling B', the string of rods whereof it forms a part having been "lost" by reason of a broken pin b². The action of the slips in this instance differs from that above described by the slips' not rocking over the shoulder 6. Here the lower ends of the slips separate enough to admit the box and then clamp it firmly as pull is exerted on the socket. Under these conditions the slips are concentric (having expanded to the original diameter of blank 20^a), accurately fit the barrel, and snugly encircle the box b'.

In Fig. 8 the slips are shown as grasping the nib of a broken rod as well as the end of an adjacent box. A double hold is thus effected. These few examples of widely different character will serve to indicate the universal adaptability of my improved slip socket.

In disengaging the socket from the rod or coupling, after the latter has been recovered, the cap 2 is removed, the spring 4 is withdrawn, and the slips are forced upwardly into the enlarged portion of the barrel to loosen their hold on the recovered part. Should it happen, however, in the seizing of a rod in

the lower portion of compartment 3^b, or a box or coupling in compartment 3^a, that the slips had been extended upward as far as the compression of the spring would allow and the 5 upper ends of the slips had been expanded against the wall of the enlarged portion of the bore and could separate no further, the slips may be forced upwardly until their upper ends engage the tapered shoulder a' and 10 are rocked inward thereby so as to separate their lower ends enough to loosen the hold on the recovered part, it being noted in this connection that the slips are capable of rocking longitudinally very slightly with respect to each other by reason of the nature 15 of the engagement between the side edges of the slips, as illustrated in Fig. 1.

The shoulder a' also serves as a stop to prevent the slips from jamming the threads 20 of the barrel, and to protect the threads from injury otherwise by objects approaching them from below.

Having thus described my invention, what I claim is:

- 25 1. A slip socket designed to operate within well tubing of a given diameter, the same comprising a barrel of substantially the maximum diameter that will operate within said tubing, said barrel having a downwardly convergent frusto-conical inner surface providing a "choke", means at the upper end of the barrel to permit the same to be lowered into a well, and a set of slips yieldingly sustained in contracted condition within the 30 "choke" of the barrel, and having a taper corresponding substantially to that of the inner surface of the barrel, the upper portion of the barrel having a cylindrical inner surface to permit the slips to recede into the 35 same, and the outer surface of each slip being so shaped as to bear only adjacent its edges upon the frusto-conical surface of the barrel when the slips are in contracted condition.
- 40 2. A slip socket comprising a barrel having a lower downwardly converging frusto-conical inner surface providing a "choke", the inner surface of the intermediate portion of the barrel being cylindrical in shape, and the upper end portion of the barrel being thickened and provided with internal screw threads, a screw threaded cap engaging said screw threads and removable from the barrel, the inner surface of the barrel between 45 the threads and cylindrical surface being gradually tapered upwardly and inwardly to provide an annular cam surface, and a set of slips yieldingly sustained in contracted condition within the "choke" of the barrel, each slip being provided at its upper end portion with an inclined surface complementary to said cam surface, and adapted to engage the latter for rocking the slips to release the same from any tool which it has 55 gripped.

3. A slip socket comprising a barrel having a downwardly converging frusto-conical inner surface providing a "choke", and a set of slips yieldingly sustained in contracted condition within the "choke" of the 70 barrel, and having a taper corresponding substantially to that of said frusto-conical surface, each slip being provided at its upper end with a recess at one of its side edges, and a projecting finger at its other side edge, the 75 fingers of the slips engaging the recesses of the adjacent slips, and the slips being readily detachable from one another by a radial movement of either slip.

In testimony whereof, I hereunto affix my 80 signature.

ERNEST J. SHAFFER.
